UNITED STATES PATENT OFFICE.

EDMOND VINCENT BENOIT, OF MONTREAL, QUEBEC, CANADA.

CAP EXTRACTOR.

Application filed April 9, 1927. Serial No. 182,435.

The present invention relates to improvements in cap extracting devices and has for its primary object to provide a device adapted for conveniently extracting the closure caps of milk bottles and similar containers.

A further object of the invention is the provision of an extracting device which will permit positive extraction of a milk bottle cap without greatly mutilating the same.

10 Another object of the invention is the provision of an extracting device of the above character which can also be efficiently employed to stir the contents of the bottle.

15 Still another object of the invention is the provision of an extracting member of the above type which is simple and durable of construction and which can be manufactured at a relatively low cost.

20 Other objects and advantages of the invention will become apparent as the description progresses.

In the accompanying drawing forming a part of this specification and in which like reference characters are employed to designate corresponding parts throughout the same:

25 Figure 1 is a side elevational view of an extracting device constructed in accordance with my invention;

30 Figure 2 is a top plan view of the same;

Figure 3 is a side elevational view of the device partly inserted in the neck of the bottle and through the cap thereof;

Figure 4 is an edge view of the device in extracting position;

Figure 5 is an enlarged vertical sectional view taken on the line 5—5 of Figure 2;

Figure 6 is a horizontal sectional view taken on the line 6—6 of Figure 3; and

40 Figure 7 is a similar view taken on the line 7—7 of Figure 4.

Referring to the drawing, wherein for the purpose of illustration is shown a preferred embodiment of the invention, the numeral 10

45 generally designates the body of the device which is in the form of an elongated flat bar, preferably of metallic construction, embodying a relatively long blade portion 11 and a substantially shorter handle section 12. One

50 end of the blade section 11 is tapered to form a piercing element 13, the edges being beveled so that the piercing element can be easily forced through a common bottle cap.

The intermediate portion of the handle bar 55 10 is formed with transversely extending opposed slots 14. The other extremity of

the handle section 12 is formed to provide a reduced central tongue 15 relatively narrow with respect to the width of the handle section. Rigidly attached to the handle section 12 of the body and formed for convenient use of the device is a handle member 16 comprising a flat metallic bar substantially equal in width to the width of the body 10 bent in substantially elliptical formation, the ends terminating adjacent the transverse slots 14 in the body and provided with laterally projecting flanges 17. The intermediate portion of the handle arranged on the outer portion of the body is provided with a transversely elongated recess through which the tongue 15 is extended. The inner ends of the handle 16 are secured to the handle section of the body by means of a transverse rivet 18 thereby providing a solid 75 handle structure.

In use, the blade section 11 is forced through the center of the milk bottle cap as shown in Figures 3 and 6 forming an elongated slot in the center of the cap. When the blade has been inserted entirely through the cap and the flanges 17 engaged on the cap, the device is rotated through an arc of approximately 45°, the slots 14 being in registration with the cap so that the body may be rotated at a transverse position with respect to the slot in the cap without mutilation. In this position, the extractor and cap may be readily withdrawn from the bottle and the blade stirred in the upper portion of the bottle to thoroughly mix the contents.

From the foregoing description, it will be readily noted that the present invention provides a simple and compact device for conveniently extracting the closure caps of milk bottles and capable of performing the additional function of a stirring device to thoroughly mix the milk or other contents.

It is to be understood that the form of my invention herewith shown and described is to be taken as the preferred example of the same, and that various changes as to the shape, size and arrangement of parts may be resorted to without departing from the spirit of the invention or the scope of the subjoined claims.

Having thus described my invention, I claim:

1. A device of the character described comprising a flat body bar tapered at one end having a pair of transverse slots ad-

5 jacent its opposite end and extending inwardly from the side edges to a point intermediate to the said side edges, a handle formed of a continuous flat strip folded over the upper end of the bar and extending to a point above the bar slots where it is bent outwardly at right angles from said bar thereby providing a pair of laterally projecting flanges, whereby the device will be prevented
10 from further downward movement.

2. A bottle cap extracting device comprising a body bar, having slots adjacent the upper end thereof and extending from the

15 side edges of said bar to an inward intermediate position, a handle formed at the upper end of the bar and having two laterally projecting flanges above the said slots and a relatively long portion of the body bar extending below the handle, said lower portion of the bar being tapered at the end 20 for cap piercing purposes and further adapted to mix the bottle contents by agitating the device.

In witness whereof I have hereunto set my hand.

EDMOND VINCENT BENOIT.
